CLAIM

The ornamental design for a trench type FPC (flexible printed circuit) connector, as shown and described.

DESCRIPTION

FIG. 1 is a perspective view of a trench type FPC (flexible printed circuit) connector, showing my new design;

FIG. 2 is a front levation view thereof;

FIG. 3 is a back levation view thereof;

FIG. 4 is a left side levation view thereof;

FIG. 5 is a right side levation view thereof;

FIG. 6 is a top plan view thereof; and,

FIG. 7 is a bottom plan view thereof.
